UNITED STATES PATENT OFFICE.

WILLIAM J. MARSHALL, OF EAST BOSTON, MASSACHUSETTS.

FIRE-HOSE NOZZLE.

Application filed August 14, 1923. Serial No. 657,340.

To all whom it may concern:

Be it known that I, WILLIAM J. MARSHALL, a citizen of the United States of America, and a resident of East Boston, in 5 the county of Suffolk, State of Massachusetts, have invented certain new and useful Improvements in Fire-Hose Nozzles, of which the following is a specification.

This invention relates to fire hose nozzles 10 and has for its object the provision of a device of this character by which a direct stream of water may be directed upon the fire, or a plurality of smaller streams may be discharged in various directions, either 15 with or without the direct stream in action.

Another object of the invention is to provide such a device with rearwardly extending discharge openings through which streams may be directed onto the hoseman 20 or hosemen, whereby these men may be thoroughly drenched when subjected to intense heat.

A further object of the invention is to provide these rearwardly extending discharge 25 openings with valves, whereby said openings may be closed when desired.

The invention consists of a casing having a valved nozzle of any well known construction mounted on its outer end, to discharge a main direct stream, combined with 30 a revoluble member having a plurality of smaller discharge openings through which additional smaller streams may be discharged in various directions.

35 The invention further consists in novel valve mechanism by which said revoluble member may be placed in and out of action at will.

The invention further consists of novel 40 means for controlling the discharge of water through the rearwardly extending discharge openings.

The invention further consists of certain 45 novel features of construction and arrangement of parts which will be understood readily by reference to the description of the drawings and to the claims to be hereinafter given.

For the purpose of illustrating the invention, one preferred form thereof is shown in 50 the drawings, this form having been found to give satisfactory and reliable results, although it is to be understood that the various instrumentalities of which the invention 55 consists can be variously arranged and organized, and that the invention is not

limited to the precise arrangement and organization of the instrumentalities as herein shown and described, except as required by the scope of the appended claims. 60

Of the drawings:

Figure 1 represents a longitudinal section of a fire hose nozzle embodying the principles of the present invention.

Figure 2 represents an inverted plan of 65 the revoluble hollow member for discharging a plurality of small streams in various directions.

Figure 3 represents a vertical section of a portion of the casing and the slidable valve 70 therein for closing the lateral ports in said casing.

Figure 4 represents a horizontal section, 75 on line 4, 4 on Figure 3, with the slidable pins of the valve cross member in retracted position, and

Figure 5 represents a similar view with the ends of said pins disposed in sockets in the inner face of the valve member.

Similar characters indicate like parts 80 throughout the several figures of the drawings.

In the drawings, 10 is a casing, one end of which is provided with the internal thread 11 by which it may be secured to 85 the fire hose.

The opposite end of the casing is provided with an external thread 12 by which a valved nozzle 13 may be secured thereto.

Any well known form of nozzle 13 may be 90 used, such, for instance, as the Callahan nozzle illustrated in the drawings.

The main stream of water from the fire hose is discharged through this nozzle 13.

Usually when a fire has been located in 95 a cellar or some similar place, it has been found necessary, or at least desirable, to substitute for the direct main stream a plurality of smaller streams which may be directed in various directions. 100

Generally when this is done, the main nozzle is removed from the casing and another form of nozzle is substituted therefor. It is a great disadvantage to be obliged to take time to make these changes as, in 105 the meantime, the fire will be making headway and possibly to such an extent as to get beyond control.

As a consequence, it has been found advantageous to mount permanently upon the nozzle casing an additional nozzle member 110-14 which may be used in connection with

the main stream nozzle 13, or independently thereof.

This additional nozzle member 14 is hollow and is revolvably mounted upon the casing 10 opposite to a plurality of lateral ports 15 therein, one end of said member contacting with a peripheral flange 16 on the casing 10 and the opposite end thereof contacting with the end of a cylindrical extension 17 to said casing.

The inner end of the extension 17 and outer coacting end of the member 14 are each provided preferably with annular raceways in which are disposed a plurality of anti-friction members, such as the balls 18 shown in Fig. 1.

The member 14 has a plurality of projections extending therefrom at different angles, each of which has a discharge opening therethrough.

Of these projections, a portion thereof, namely the projections 19, extend toward the front at an angle to the axis of the casing 10, while the projections 20 extend angularly toward the rear.

Another set of projections 21 are disposed midway of the length of the member 14 and are substantially tangential to the inner face thereof, so that the water being discharged therethrough will cause the hollow member 14 to be rotated about the axis of the casing 10, thereby throwing the streams in every direction.

The projections 20 have discharge openings 22 therethrough, each of which is adapted to be closed by the rotatable valve 23 therein.

The valve 23 has secured to one end a collar 24, provided with a wing projection 25 by which the valve 23 may be moved about its axis to open the discharge opening 22.

The opposite end of the valve plug 23 has secured thereto a bevel gear 26 meshing with an annular gear 27 surrounding one end of the hollow member 14.

By means of this construction, when one valve 23 is opened, the other valves 23 will be opened simultaneously, and likewise all of them will be closed at the same time without regard to which actuating device 24, 25 is moved by the operator.

Obviously, the discharge of water through these openings may be regulated by movement of the valves 23 so that a full stream may be discharged through the openings 22, or any lesser amount as desired.

When the hosemen are being subjected to intense heat, these valves 23 will be opened to allow streams to be discharged over the hosemen to keep them thoroughly drenched.

When the hosemen are fighting a cellar fire and the nozzle is extended through an opening cut in the floor, these valves 23 will preferably be open.

When, however, the heat from the fire is

not so intense as to inconvenience hosemen, the valves 23 may be closed and streams discharged only from the openings through the projections 19, 21.

At this time the main stream through the nozzle 13 may be in action or not, according to the nature of the fire being fought.

Where the nozzle is being used at some distance from the fire, it is desirable to place the member 14 entirely out of action and permit the entire supply of water to pass through the nozzle 13.

The means for accomplishing this result is as follows:

To a flange 28 on the inner face of casing 10 is threaded one end of a tube 29, the opposite end of which is provided with a valve seat 30.

This tube 29 is spaced from the inner face of the casing 10, thereby forming an annular chamber in which the tubular valve member 31 is adapted to be reciprocated endwise.

This valve member 31 has on its inner face midway of its length, an inclined shoulder 32 adapted to coact with the valve seat 30 to prevent leakage at this point, and on the outer face of said valve member 31 is an inclined shoulder 33 adapted to coact with the valve seat 34 on the outer end of the extension 17 of the casing 10.

The valve member 31 has a plurality of lateral ports 35 which are adapted to register with the ports 15 in the casing 10 when the valve member 29 is moved outwardly as in Fig. 3.

When the valve member 31 is in the position shown in Fig. 1, the ports 15 are closed thereby, and no water can be admitted to the hollow member 14, and the shoulder 32, 33 will be in contact with the valve seats 30, 34 so that there can be no leakage into the hollow member 14.

When the valve member 31 is moved outwardly, the ports 35 will be brought into a position beyond the valve seat 30 and opposite the ports 15 in the casing 10, and the water passing through the casing 10 will then pass through the ports 35, 15 into the hollow member 14 and revolve the same.

In the inner face of the valve member 31 and near the outer end thereof are the oppositely disposed sockets adapted to receive the ends of the pins 37 slidably mounted in the cross bar 38 extending diametrically of the bore of the valve member 31.

This cross bar 38 has a cylindrical opening therein midway of its length, through which extends the threaded outer end 40 of the rod 41.

The threaded end 40 has clamp nuts 42 thereon by which said rod 41 may be clamped to said cross bar when properly positioned therein.

The slidable pins 37 are in the position indicated in Fig. 4 when the cross bar 38 is

assembled in the valve member 31, and when the cross bar 38 is properly positioned in said valve member 31, these pins 37 are moved outwardly in said cross bar 38 until their outer ends are positioned in the sockets 36.

When thus assembled, the cross bar 38 may be oscillated freely about the axis of said pins 37.

When the pins 37 have been moved outwardly, the threaded end 40 will be inserted through the opening in the cross bar 38, and the nuts 42 thereon clamped against said cross bar.

This threaded end 40 when positioned in the cross bar 38 will retain the slideable pins 37 in their outward position and prevent their ends from being displaced from the sockets 36.

The opposite or inner end of the rod 41 is connected by a pin 43 to the outer end of a crank 44 secured by a pin 45 to a shaft 46 extending through a stuffing box 47 in the side of the casing 10.

The outer end of the shaft 46 has a crank 25 actuating member 48 secured thereto by a pin 49, said member preferably being in the form of a disk as shown in Fig. 1.

The disk 48 has a depression 50 in its inner face into which normally extends the outer end of a locking bolt 51 forced outwardly by a spring 52 in a socket 53 in a boss formed upon the casing 10.

When the valve member 31 is in the position indicated in Fig. 1, the bolt 51 will extend into the depression 50, thereby preventing the rotation of the crank shaft 46 and retaining the valve member 31 in its closed position.

In the depression 50 is mounted the head 40 54 having a stem 55 extending outwardly, with a pad 56 mounted on the outer end thereof, said pad being spaced from said disk a distance equal to the length of that part of the bolt 51 which is disposed in the depression 50.

When it is desired to slide the valve member 31 into its open position, the operator presses upon the pad 56 and releases the bolt 51 from the depression 50 so that the disk 48 may be rotated about the axis of the crank shaft 46, thereby moving the crank 44 into a position diametrically opposed to that shown in Fig. 1, and through the rod 41 moving the valve member 31 endwise.

This makes a very simple form of nozzle for fire hose which may be used in a variety of ways to suit different conditions.

It is believed that the operation and many advantages of this improved nozzle will be understood readily without further description.

Having thus described my invention, I claim:

1. In a device of the class described, the

combination of a casing having lateral 65 ports; a valved nozzle on one end of said casing; a hollow member surrounding said casing opposite said ports and provided with a plurality of discharge openings; a tubular member fitting the inner wall of said casing 70 and provided with ports adapted to register with the casing ports; and a crank within said casing for moving said tubular member endwise.

2. In a device of the class described, the 75 combination of a casing; a valved nozzle on one end thereof; a hollow member surrounding said casing and communicating with the interior thereof by a plurality of ports; a slideable valve within and fitting the inner 80 wall of the casing for opening and closing said ports; an oscillating member in one end of said valve; a rod, one end of which extends through and is clamped to said member; and crank mechanism articulated to the 85 opposite end of said rod for imparting endwise movement to said valve.

3. In a device of the class described, the combination of a casing; a valved nozzle on one end thereof; a hollow member surrounding 90 said casing and communicating with the interior thereof by a plurality of ports; a slideable valve within the casing for opening and closing said ports; an oscillating member in one end of said valve, provided with 95 slideable aligned pins, the ends of which are adapted to be positioned in oppositely disposed sockets in the inner face of said valve; a rod, one end of which extends through and is clamped to said member; and crank mechanism articulated to the opposite end 100 of said rod for imparting endwise movement to said valve.

4. In a device of the class described, the 105 combination of a casing; a valved nozzle on one end thereof; a hollow member surrounding said casing and communicating with the interior thereof by a plurality of ports; a slideable valve within said casing for opening and closing said ports; valve actuating 110 mechanism within said casing including a crank; a crank shaft extending through the wall of the casing; a rod the opposite ends of which are pivotally connected respectively to said crank and said valve; and means on the outer end of said shaft for rotating said shaft.

5. In a device of the class described, the combination of a casing; a valved nozzle on one end thereof; a hollow member surrounding 120 said casing and communicating with the interior thereof by a plurality of ports; a slideable valve within said casing for opening and closing said ports; valve actuating mechanism within said casing including a crank; a crank shaft extending through the wall of the casing; a member on the outer end of said crank shaft for rotating said

shaft; and means mounting on said casing and coacting with said member to lock it when the valve is covering said ports.

6. In a device of the class described, the combination of a casing; a valved nozzle on one end thereof; a hollow member surrounding said casing and communicating with the interior thereof by a plurality of ports; a 5 slideable valve within said casing for opening and closing said ports; valve actuating mechanism within said casing including a crank; a crank shaft extending through the wall of the casing; a member on the outer end of said crank shaft for rotating said 10 shaft; and a spring-pressed bolt coacting therewith for locking said member when the valve is covering said ports.

7. In a device of the class described, the combination of a casing; a valved nozzle on one end thereof; a hollow member surrounding said casing and communicating with the interior thereof by a plurality of ports, said member having a plurality of discharge 20 openings therein; a rotatable valve for closing a discharge opening; and means carried by and rotatable about the axis of said hollow member for actuating said valve.

8. In a device of the class described, the combination of a casing; a valved nozzle on one end thereof; a hollow member surrounding said casing and communicating with the interior thereof by a plurality of ports, said member having a plurality of discharge 30 openings therein; rotatable valves for closing certain discharge openings; a gear on each rotatable valve; and an annular gear surrounding said hollow member and meshing with said valve gears.

9. In a device of the class described, the combination of a casing; a member surrounding said casing and communicating with the interior thereof; a plurality of projections with discharge openings therein extending from said member at various angles; means for controlling the flow of liquid 40 to said member; valves independent of said

controlling means for closing certain of said discharge openings; and means for simultaneously actuating said valves.

10. In a device of the class described, the combination of a casing; a hollow member surrounding said casing and communicating with the interior thereof by a plurality of ports; a slideable valve within and fitting the inner wall of the casing for opening and closing said ports; an oscillating member in one end of said valve; a rod, one end of which extends through and is clamped to said member; and crank mechanism articulated to the opposite end of said rod for imparting endwise movement to said valve. 55

11. In a device of the class described, the combination of a casing; a hollow member surrounding said casing and communicating with the interior thereof by a plurality of ports; an oscillating member in one end of said hollow member provided with slideable aligned pins, the ends of which are adapted to be positioned in oppositely disposed sockets in the inner face of said valve; a rod, one end of which extends through and is clamped to said member; and crank mechanism articulated to the opposite end of said rod for imparting endwise movement to said valve. 65

12. In a device of the class described, the combination of a casing; a hollow member surrounding said casing and communicating with the interior thereof by a plurality of ports, said member having a plurality of discharge openings therein; rotatable valves for closing certain discharge openings; a gear on each rotatable valve; and an annular gear surrounding said hollow member and meshing with said valve gears. 70

Signed by me at 746 Old South Bldg., 75 Boston, Mass., this 13th day of August, 1923.

WILLIAM J. MARSHALL.
